UNITED STATES PATENT OFFICE.

ROBERT O. BOARDMAN, OF GRAND RAPIDS, MICHIGAN, ASSIGNEE TO MERGENTHALER LINOTYPE COMPANY, A CORPORATION OF NEW YORK.

TYPOGRAPHICAL COMPOSING-MACHINE.

1,075,137.

Specification of Letters Patent.

Patented Oct. 7, 1913.

Application filed January 16, 1912. Serial No. 671,464.

To all whom it may concern:

Be it known that I, ROBERT O. BOARDMAN, a citizen of the United States, a resident of Grand Rapids, county of Kent, and State of Michigan, have invented a new and useful Improvement in Typographical Composing-Machines, of which the following is a specification.

My invention has reference to typographical composing machines, as for instance, linotype machines of the general organization represented in Letters Patent of the United States, No. 436,532, to O. Mergenthaler, wherein circulating matrices are released from a magazine in the order in which their characters are to appear, in print and then assembled in line together with expanding spacers, the composed line transferred to the face of a mold, the mold filled with molten metal to form a slug or linotype against the matrices which produce the type characters thereon, and the matrices thereafter elevated and returned through a distributing mechanism to the magazine from which they started.

More particularly, the invention relates to the employment of a number of magazines containing fonts or sets of matrices representing different sizes or styles of type, in such manner that any font may be brought into action at will, so that matter may be produced with faces represented by the matrices in one magazine, or by a combination of faces represented by the matrices in two or more magazines. The particular mechanism for selecting and assembling the matrices may be of any known or desired type and constitutes no part of the present invention, which is rather directed to the devices for restoring them to the place from which they started. Preferably I employ a series of superposed stationary magazines and a single distributing mechanism, in combination with adjustable means adapted to receive the matrices from the distributing mechanism and to convey them to any of the magazines, the said means being adjustably mounted to permit them to register with the selected magazine so as to deliver the corresponding matrices thereto.

I am aware that it is old in the art to employ a series of magazines in connection with a single distributing mechanism and adjustable means whereby the matrices may be delivered to any selected one, and I lay

no claim to such combination broadly. For instance, a pivotally mounted throat has been used for this purpose in connection with a limited number of magazines; or a channeled passageway has been employed between the distributor and the several magazines, the said passageway being provided with adjustable switches, whereby the matrices are deflected from the passageway into the selected one. In the present instance I use a throat or deflector which is movable bodily or as a whole in a direct path and without changing its angular position, and is thus made to register with any one of the several magazines. This construction enables me to employ a materially larger number of magazines than is possible in connection with an angularly-movable pivoted throat, quite apart from the novelty of the arrangement itself. More specifically, I connect the distributing mechanism with a plurality of superposed magazines by a passageway arranged in proximity to the mouths or entrances of all of them, and in this passageway I dispose the movable throat, which is arranged to slide vertically past all of the magazines and in such manner that it may be caused to register with any one thereof. I have also provided means whereby the channels of the movable throat are caused at all times to fit closely into the corresponding channels in the passageway so as to preserve their continuity, and also means whereby the entrances or mouths of the magazines between the selected one and the distributing mechanism are shut off, in order to prevent the accidental displacement of the matrices or their passage into a wrong magazine. These and other features of construction will be apparent from the drawing and the specification and claims.

In the drawing I have shown my invention applied to a linotype machine, as before stated, but obviously it may be similarly used in connection with type-setting machines, or in fact any kind of typographical machines, and in order to handle dies or type as well as matrices; and I therefore desire it to be distinctly understood that I do not limit myself to any specific form or embodiment except in so far as such limitations are specified in the claims.

Referring to the drawing: Figure 1 is a transverse vertical section through the magazines and distributing mechanism of a line-

type machine, having my invention applied thereto; Fig. 2 is a detail view, showing the relation of the channel partitions of the movable throat to the corresponding channel partitions of the main passageway; and Fig. 3 is a detail view of one of the plates used to shut off the magazine mouths.

Referring to the drawing, the distributing mechanism A is or may be of any ordinary type, as disclosed for instance in the Mergenthaler patent already referred to, and the matrices B are delivered therefrom into the appropriate channels of the passageway C, from which in turn they pass through the curved throat or deflector D into the selected one of the magazines E. As previously indicated, any convenient number of magazines E may be employed and they are preferably arranged in superposed position, as indicated in Fig. 1. Their mouths or entrances are located in proximity to the common passageway C, which is of sufficient extent to communicate with all of them. The throat D is shown by full lines in operative relation to the uppermost of the magazines, but is movably mounted so that it may be caused to register with any other one thereof, as indicated by dotted lines. In the particular form illustrated, the throat is arranged so that it may be slid vertically for the purpose noted, it being guided by laterally projecting lugs D¹, which engage in the vertical guide slots C¹ located between the passageway C and the magazine entrances. The desired adjustment of the vertically movable throat may be secured in any convenient manner, either manually or mechanically. In the present instance the throat is shown as provided with handles or knobs F, indicated by dotted lines, whereby it may be manually slid to the required position. When the throat D is in operative relation to the upper magazine E, as shown in the drawing, the matrices B pass from the distributing mechanism A directly therethrough into the magazine. When, however, it is slid or shifted to a different operative position, as indicated by dotted lines, the matrices pass downward from the distributing mechanism first through the passageway, then to the throat, and thence into the selected magazine. In order to insure the delivery of the matrices to this magazine and to prevent their edgewise deflection, I provide flexible means which shut off the mouths or entrances of all the magazines between the selected one and the distributing mechanism, and also assist in the proper guidance of the matrices in the passageway C. In the specific instance illustrated, these flexible means comprise a series of bars G (see Fig. 3) pivotally connected to each other at G¹ and provided with a series of rollers G² which track upon a suitable guideway G³. The pivotally connected bars G are at-

tached to the vertically movable throat D, so that when the latter is adjusted in relation to any lower selected magazine E, the mouths of the magazines above it are shut off by the bars, which then constitute one side of the passageway C.

The passageway C is formed with channels for the respective matrices, these channels being separated by the vertical partitions H. Similarly the throat D is provided with corresponding channels, which are formed by the partitions J. In order to preserve the continuity of these channels, and to secure at all times a continuous passage from the distributor to the corresponding channels of the selected magazine, the partitions J of the throat D are slidably located in immediate proximity to the partitions H of the passageway C. In the form illustrated in the drawing (see Fig. 2), the partitions H of the passageway are double, with a sufficient space between the two sections to receive the single partitions J of the movable throat. Because of this construction and arrangement, it will be seen that whatever the relative position of the throat and the passageway, there will always be a continuous track or way for the matrices delivered from the distributing mechanism.

I have herein described my invention as applied by way of example in a specific and preferred form, but obviously many changes and variations may be made therein without departing from its spirit.

Having thus described my invention, its construction and mode of operation, what I claim and desire to secure by Letters Patent of the United States is as follows:

1. In a typographical composing machine, the combination of distributing mechanism, a plurality of magazines, a common passageway leading from said distributing mechanism to said magazines, and a throat or deflector mounted in said passageway to direct the type or matrices into a magazine, the said throat or deflector being movably mounted so that it may be brought into registry with any selected magazine.

2. In a typographical composing machine, the combination of distributing mechanism, a plurality of magazines, a common passageway leading from said distributing mechanism to said magazines, and a throat or deflector mounted in said passageway to direct the type or matrices into a magazine, the said throat or deflector being movable as a whole relatively to the distributing mechanism and so as to register with any selected magazine.

3. In a typographical composing machine, the combination of distributing mechanism, a plurality of superposed magazines, a vertical passageway leading from said distributing mechanism to said magazines, and a throat or deflector mounted in said

passageway to direct the type or matrices into a magazine, the said throat or deflector being movable in a vertical direction to register with any selected magazine.

5 4. In a typographical composing machine, the combination of distributing mechanism, a plurality of magazines, and a throat or deflector to receive type or matrices from the distributing mechanism and 10 deliver them to a magazine, the said throat or deflector being mounted so that it may be moved past the entrances of the several magazines to register with any selected one thereof, together with means to shut off the 15 entrances of the magazines which are located between the selected one and the distributing mechanism.

5. In a typographical composing machine, the combination of distributing mechanism, a plurality of magazines, and a 20 throat or deflector to receive type or matrices from the distributing mechanism and deliver them to a magazine, the said throat or deflector being mounted so that it may be moved past the entrances of the several 25 magazines to register with any selected one thereof, together with flexible means connected to the throat or deflector to shut off the entrances of the magazines which are located between the selected one and the 30 distributing mechanism.

6. In a typographical composing machine, the combination of a distributing mechanism, a plurality of magazines, and a 25 channeled passageway extending from the distributing mechanism past the entrances of the several magazines, with a channeled

throat or deflector movable in said channeled passageway to register with any selected magazine, the corresponding channels of the passageway and throat or deflector fitting each other to preserve their continuity in the several operative positions of the throat or deflector.

7. In a typographical composing machine, the combination of a plurality of superposed magazines, a distributing mechanism above the level of the said magazines, vertical channels to guide the type or matrices falling from the distributing mechanism, and a throat or deflector to receive the type or matrices falling through the said channels, said throat or deflector being adjustable vertically so that it may direct the matrices into any one of the magazines.

8. In a typographical composing machine, the combination of a plurality of superposed magazines, a distributing mechanism, fixed parallel plates extending past the entrances of all the said magazines to guide the type or matrices falling from the distributing mechanism, and a throat or deflector movable at will into operative relation to any selected one of the magazines and adapted to direct the type or matrices thereinto.

In testimony whereof I hereunto set my hand this 14th day of December, 1911, in the presence of two attesting witnesses.

ROBERT O. BOARDMAN.
